METHOD OF PRODUCING KNITTED GOODS

Jacob A. Goodman, Indianapolis, Ind.

Application June 20, 1932, Serial No. 618,336

9 Claims. (Cl. 66—149)

The invention pertains to knitting and is applicable to that type of knitting which is commonly carried out by machine. Machine knitting is conventionally done on a plurality of knitting needles or other instrumentalities usually lying parallel to each other in a band describing a plane, cylinder or other geometric surface. Usually each needle produces a loop in each course to make wales longitudinally of the fabric, and the number of active needles in the bank determines the width or lateral extent of the fabric being knitted. The fabric in the course of production usually is attached to a take-up mechanism which serves to draw the fabric away from the knitting instrumentalities as it is formed. The take-up mechanism applies a take-up tension to the fabric which is transmitted therethrough to the course of loops in the process of being knitted and to the knitting instrumentalities. Thus the take-up tension plays an important part in determining the size of the loops being knitted. It also draws the fabric taut and holds the same out of the path of the needles during their upward movement to prevent them from piercing through the fabric. Knitting machines are usually designed in such manner as to make the application of a take-up tension imperative.

The take-up mechanism may involve the use of various tensioning devices, weights being conventionally employed in many machines such as those of the Cotton type. Such mechanism necessarily imposes a stress upon the fabric which tends to distort the same particularly in the course in the process of formation on the needles, so that an undue amount of tension is likely to strain or rupture the fabric loops and elongate or pull out the loops in the course being formed. Such dangers are especially great in fabrics knitted of fine gauge yarn of low tensile strength. Again, the take-up tension is transmitted through the fabric to the needles, and the needles being delicate and fine are likely to be strained, bent or broken if the take-up tension is excessive, particularly where the fabric being knitted is composed of heavy or reinforced yarn of considerable tensile strength which can successfully withstand relatively great tension. The danger of strain on the various parts is, of course, increased by reason of the movement of the needles during the progress of the knitting operation.

While in the knitting of relatively wide fabrics there is no considerable difficulty in providing a take-up tension which will successfully perform its function without danger of injury to either the fabric or the needles of the knitting machine, in the formation of narrow fabrics and fabrics which are materially decreased in width at various stages of knitting there is considerable danger that the take-up tension will be excessive and

reach strain producing proportions such as will injure the fabric and the knitting instrumentalities. In the knitting of garment fabrics, for example, it is common practice to diminish the number of active needles in the bank to produce portions of narrower width adapted to shape and conform the garment to parts of the body, and the take-up stress at the knitting point will increase the narrower the fabric is made. Thus in producing certain embodiments of the full fashioned stocking heel construction disclosed and claimed in my copending application, Serial No. 563,184, filed September 16, 1931, it is necessary to knit portions of the heel tabs of very narrow width with about three or four knitted loops in a course. Under such circumstances there are only six or eight loops in the process of formation and a corresponding number of knitting needles which carry the entire stress imposed by the take-up tension, and unless such tension is relatively low both the fabric and needles are likely to be injured as above described.

The present invention has for its primary object the production of fabrics of any desired degree of narrowness on knitting machines without injury to the fabric or the needles under the tension imposed thereon while at the same time maintaining the operating efficiency of the take-up mechanism.

In its broadest aspect the invention involves the control of the tension of the take-up mechanism in accordance with the width of the fabric and the number of needles utilized so that the effective tension and stress distributed to each needle and the loop on each needle will be of proper proportions. Such regulation is particularly important where the tension produced by the take-up mechanism is such as would ordinarily impose a serious strain. It is possible, I have discovered, to control the effective tension or stress upon the fabric and needles without necessarily reducing the actual tension originating in the take-up mechanism.

If the fabric being knitted is materially reduced in width at portions of its length the effective tension will be varied accordingly so that in the narrower portions it will not be so great as to strain the fabric, or cause the formation of undesirable elongated courses which might produce streaks in the finished fabric.

The narrower the fabric being knitted,—and hence the smaller the number of fabric loops and the fewer the active needles,—the greater will be the stress imposed by the take-up mechanism on each individual loop and needle. To produce an effective tension of suitable magnitude I propose to absorb the stress produced in the fabric by the take-up mechanism in such manner that the portion of the stress imposed upon each in-

dividual needle and loop will not be sufficiently great to cause injury. To this end supplementary means adapted to receive part of the stress that would otherwise be sustained by the needles 6 are supplied during the knitting process and as needed.

- The supplementary stress absorbing means may conveniently comprise one or more sections of auxiliary fabric which may be formed simultaneously with the main fabric on additional needles of the machine. The auxiliary fabric will have a connection with the take-up mechanism and can be taken up thereby together with the main fabric. The same may be knitted of sufficient width to carry substantially the entire stress produced by the take-up mechanism, this being desirable where the main fabric is of very narrow width, or its width may be such that the stress will be shared with the main fabric. 10 In any case there will be no danger of strain to the main fabric loops or the needles. If the main fabric is narrowed the auxiliary fabric may be widened commensurately so that during the formation of each course each needle and loop 15 will carry the same take-up stress, or as in the practical embodiment illustrated in the drawing the auxiliary fabric may be knit of uniform width throughout its length and sufficiently ample to carry the take-up tension.
- Having now stated the nature of my invention, I will now describe one practical embodiment thereof, reference being had to the accompanying drawing in which:

Fig. 1 illustrates the application of my invention in the knitting of the heel portion of a full fashioned stocking on a flat knitting machine; and,

Fig. 2 illustrates a stocking blank resulting from the use of my invention.

Fig. 1 shows conventionally, the needle bank 11 and take-up mechanism 12 of a full fashioned legger. Knitting has progressed to produce the leg and angle portions 14 of the stocking up to the course 15-16. Under prior art practice knitting continues to produce loopers courses 16 to line 17-17 and then the two disconnected heel tabs 18 are knitted. When sufficient fabric is knitted to complete the heel tabs, usually a course of loops is followed by several loopers courses before the fabric is removed from the machine. The heel tabs 18 are knitted on the restricted number of needles 19 represented by the width of the tabs and due to narrowing in the heel there is a further diminution of the number of active needles. Throughout the knitting of the heel tabs the entire tension of the take-up 12 is carried by the restricted number of needles with a correspondingly increased stress distribution to the several needles and to the fabric loops being formed. The less active needles the greater the stress on each needle and this continues to a point where the take-up tension may distort or rupture the loops as they are knitted or, if the knitting yarn is strong as is usually the case in knitting heel tabs, until the needles are strained or bent. This causes serious damage to the machine. The danger becomes greater the narrower the fabric becomes and in knitting rounded heels, such as disclosed in my copending application above referred to, under certain embodiments of which narrowing continues until each tab is knitted on only three or four needles, the danger is so great that some adjustment of the take-up tension must be provided for.

As seen in Fig. 1, when knitting has progressed

to the course along line 15-16, I knit a number of loopers courses 16 to the line 17-17 as in prior art practice and then instead of rendering the instep needles 20 inactive, I continue knitting auxiliary fabric 21 on these needles simultaneously with the knitting of the heel tabs. Thus as the heel tabs grow in length the fabric 21 grows to the same extent and helps the needles knitting the heel tabs to carry the take-up load. By carrying out my method the loops being formed are at no time unduly stressed and there is no stress on the knitting needles that they are not equal to carrying.

As illustrated in Fig. 2 the resultant stocking blank will have the heel tabs 18 which may be narrowed to any extent desired. As clearly seen the fashioning marks 23 can be made to meet or closely approach the inside and outside selvage edges 24 and 25 respectively at the terminal course at 22 without danger of injury because the take-up tension throughout the knitting of the heel tabs has been carried at least in part by the auxiliary fabric 21. The auxiliary fabric 21 may be knitted separately as shown with its own selvage edges 26. This may be done by knitting with 25 the same yarn or the same grade of yarn used in knitting the leg and ankle fabric or can be knitted of a different kind of yarn. It is preferred to use an inexpensive strong yarn to knit the fabric 21 because this fabric is later removed in the subsequent topping operation. The fabric 21 may be produced on all or part of the needles between the heel tab needles 18, the only requirement being that there be enough needles used to knit the auxiliary fabric to amply carry the take-up stress together with the smallest number of needles used to knit heel tab courses.

In the article shown in Fig. 2 the outside and inside selvage edges 24 and 25 of the heel tabs and the line of transfer marks 23 practically come to a point at 22 and no looping of the terminal course is necessary so that looping courses are not entirely essential.

It will be appreciated that the formation of the auxiliary fabric or equivalent stress absorbing means is of particular benefit in connection with the knitting of fabrics of narrow width, such as the stocking heel tabs above described, where fashioning is resorted to in the narrow areas. The manipulation of the fabric loops by transfer mechanism as well as the stress of the take-up mechanism imposes a strain on the fabric and knitting needles and tends to distort the fabric. By the use of the method herein described the transfer operation which fashions the fabric may be more readily and efficiently carried out without danger of distortion or rupture of the fabric or the production of blind stitches.

Although I have described my invention as applied to a Cotton machine it finds application on any knitting machine in which knitting is done on a plurality of needles in a bank and the fabric taken up under tension. Although in the specific embodiment shown I narrow the heel tabs of a full fashioned stocking my invention is useful wherever knitting is done to produce fabric so narrow that the take-up tension is in danger of distorting or rupturing the loops while they are being knitted or of straining the knitting instrumentalities.

What I claim is:

1. The method of forming a fabric which comprises knitting the fabric on a plurality of knitting instrumentalities and taking up the fabric as it is formed, applying a take up tension to the

1. fabric and transmitting a stress distributed to the respective knitting instrumentalities, narrowing the fabric by diminishing the number of knitting instrumentalities engaged in knitting the fabric, and supplying means to absorb a part of the take-up tension to prevent injury when the number of instrumentalities have been diminished to such an extent that the stress distributed to them respectively approaches strain producing proportions, and withdrawing the tension absorbing means when the narrowed portion of the fabric is no longer subject to the take-up tension.

2. The method of knitting an article fabric on a plurality of knitting instrumentalities and taking up the fabric as it is formed which includes, applying a take up tension to the fabric to transmit a stress distributed to the respective knitting instrumentalities, narrowing the article fabric by decreasing the number of instrumentalities engaged in knitting the article fabric, knitting auxiliary fabric integral only at its upper end with the article fabric on instrumentalities not engaged in knitting the article fabric and applying the take up tension to the auxiliary fabric to readjust the stress distribution to prevent injury, and severing the auxiliary fabric after the take-up tension has been withdrawn from the article fabric.

3. The method of knitting a garment fabric on a plurality of knitting instrumentalities and taking up the fabric as formed, which includes, applying a take up tension to the fabric to transmit a stress distributed to the respective instrumentalities, knitting auxiliary fabric integral with the garment fabric on instrumentalities not engaged in knitting the garment fabric to receive the take up tension and readjust the stress distribution, and removing the auxiliary fabric from the garment fabric after the take-up tension is withdrawn.

4. The method of knitting a garment fabric on a plurality of knitting instrumentalities and taking up the fabric as formed which includes, applying a take up tension to the fabric to transmit a stress distributed to the respective instrumentalities, narrowing the garment fabric to form a tab by discontinuing knitting the garment fabric on a group of the instrumentalities, continuing knitting on the instrumentalities that discontinue knitting the garment fabric and forming thereon an auxiliary section of fabric subject to the take up tension integral only at its beginning end with the garment fabric to maintain a stress distribution that will prevent injury, and disconnecting the auxiliary fabric from the garment fabric after the narrowed portion of the garment fabric is no longer subject to the take-up tension.

5. The method of knitting a garment fabric on a plurality of knitting instrumentalities and taking up the fabric as formed which includes, applying a take up tension to the fabric to transmit a stress distributed to the respective instrumentalities, narrowing the fabric to form a tab by discontinuing knitting the garment fabric on a group of instrumentalities, continuing knitting on the group of instrumentalities that discontinue knitting the garment fabric to form auxiliary fabric integral with the garment fabric under the take up tension, narrowing the tab gradually as the knitting progresses, and maintaining through the auxiliary fabric a stress distribution that will prevent injury, and removing the auxiliary fabric from the garment fabric when the tension is withdrawn from the tab.

6. That method of knitting a stocking blank which comprises, narrowing the stocking fabric by knitting on a gradually diminishing number of needles while maintaining a take-up tension on the fabric, and simultaneously knitting auxiliary fabric on needles not engaged in knitting the stocking fabric to receive the take up tension, and removing the auxiliary fabric after the take-up tension has been withdrawn from the stocking fabric.

7. In the knitting of fabric upon a bank of knitting needles under a take-up tension, the method of producing a fabric blank upon a plurality of needles of the bank under a tension transmitted through the fabric to said needles, which tension if concentrated upon such blank-knitting needles might result in strain or breakage thereof, which consists in knitting the blank, and knitting other fabric connecting only at its beginning course with the blank besides the blank under said tension simultaneously with the knitting of the blank and upon needles other than the blank-knitting needles so that the tension which would otherwise be concentrated on the blank-knitting needles will be distributed between the blank-knitting needles and the needles engaged in knitting the other fabric, and severing the latter fabric from the blank after the take-up tension has been relieved.

8. The method of knitting a fabric article blank of such character as to be susceptible to injury under normal take-up tension, which comprises knitting the article blank upon needles of a needle bank which includes a group of needles additional to those engaged in knitting the blank, withdrawing the fabric as successive courses are knit by a take-up roll while applying a normal tension through said take-up roll, and during the knitting of the blank distributing the tension developed through said roll to an area of the needle bank including a plurality of needles additional to those engaged in knitting the blank so that the full tension is not concentrated on the article blank or on the particular portion of the needle bank engaged in knitting the same.

9. The method of knitting a narrow fabric article blank including narrow courses only a few wales wide and such as to be susceptible to distortion and rupture when the fabric blank during knitting is subjected to a normal degree of tension, which includes knitting the narrow article blank on needles forming a part of a needle bank wider than said blank, withdrawing the fabric of the blank as formed by a take-up roll while applying a moderate normal tension through said take-up roll, and reducing the amount of tension on the narrow blank by knitting simultaneously therewith successive courses of auxiliary fabric separate from the courses of the blank and forming no part of the finished article on an adjacent group of needles of the same needle bank and also subject to the tension applied through said take-up roll, and thereby distributing and absorbing the normal tension developed through the take-up roll, which would otherwise be concentrated on the narrow blank and the narrow group of needles knitting the same, between said article blank and the auxiliary fabric, and over an area of needles of the needle bank wider than the narrow blank, and withdrawing the auxiliary fabric after the narrow article blank has been completed and relieved of the take-up tension.
